UNITED STATES PATENT OFFICE

136,264

DESIGN FOR A COMBINED TOWEL AND WASH CLOTH RACK OR SIMILAR ARTI- CLE

Tennie L. Williams, Epworth, Ga.

Application May 27, 1943, Serial No. 110,306

Term of patent 7 years

To all whom it may concern:

Be it known that I, Tennie L. Williams, a citizen of the United States, residing at Epworth, in the county of Fannin and State of Georgia, have invented a new, original, and ornamental Design for a Combined Towel and Wash Cloth Rack or Similar Article, of which the following is a specification, reference being had to the accompanying drawing, forming a part thereof.

Figure 1 is a front elevational view of a combined towel and wash cloth rack, or similar article, showing my new design; and

Figure 2 is a side elevational view thereof.

I claim:

The ornamental design for a combined towel and wash cloth rack or similar article, as shown.

TENNIE L. WILLIAMS.
